ROTATABLE WATER GATE

Harry E. Smyser, York, Pa., assignor to S. Morgan Smith Company, York, Pa., a corporation of Pennsylvania

Application July 2, 1937, Serial No. 151,596

4 Claims. (CL. 61—22)

This invention relates to dams and more particularly to dams having movable gates.

An object of the invention is to provide an improved dam in which the damming element is in the form of a gate rotatably mounted in the dam and adapted to be swung downwardly towards the bed of the stream when it is desired to permit the free flow of water downstream.

Another object of the invention is to provide an improved dam having a sill on the bed of the stream with a longitudinal arcuate depression formed in its upper surface for the reception of a gate rotatably mounted in the dam and having a curved surface on one side, so that the gate can be disposed within the depressed portion of the sill and thereby permit free and unrestricted flow of water past the dam.

With the foregoing and other objects and advantages in view, the invention consists in the preferred construction and arrangement of the several parts which will be hereinafter fully described and claimed.

In the accompanying drawings:—

Figure 1 is a plan of a dam embodying the present invention;

Fig. 2 is a vertical longitudinal section;

Fig. 3 is a vertical transverse section taken on the line 3—3 of Fig. 2, the gate being shown in vertical or damming position;

Fig. 4 is a view similar to Fig. 3 showing the gate lowered;

Fig. 5 is an enlarged plan of the operating mechanism for the gate; and

Fig. 6 is a vertical section of a portion of the structure shown in Fig. 5.

The improved dam comprises a sill 11 formed on the bed of a stream, said sill having an arcuate depression 12 formed longitudinally in its upper surface.

At each end of the sill 11 there are upstanding end walls, one of which is indicated at 13, and the other being designated 14.

When the width of the stream is considerable and more than one gate is required for damming up the water, the intermediate end walls may be in the form of piers, as shown in Fig. 1. These piers extend upwardly a suitable distance and a bridge structure 15 spans the top of the same.

The end walls or piers 13 and 14, respectively, have pockets 16 and 17 formed therein, for the reception of the ends 18 and 19, respectively, of a rotatable dam member or gate 20.

The ends 18 and 19 are in the form of cylindrical drums, adapted to rotate within the pockets 16 and 17, respectively.

For the purpose of supporting the gate 20, a journal 21 mounted in each pocket, and carried by the respective piers 13 and 14, is disposed in a bearing 22 formed concentrically in each of the ends 18 and 19, as shown in Fig. 2.

The gate 20 comprises a segmental hollow structural steel body formed with a rear arcuate wall 23 and a flat front wall 24.

The rear wall 23 is concentrically disposed with respect to the ends 18 and 19 and also with the sill depression 12, so that when the device is rotated the gate will move in a path across the top of the sill 11 from the vertical position shown in Fig. 3, to the horizontal position shown in Fig. 4.

In order to seal the joint between the gate 20 and the sill, at a point adjacent the longitudinal edge portion 25 of the gate, the curved wall 23 is formed with an outwardly projecting sealing strip 26 adapted to bear against the upper arcuate surface 12 of the sill 11, as shown in Figs. 3 and 4.

On the upstream side of the sealing strip 26, the gate also carries an outwardly projecting flange 27, the purpose of which is to prevent foreign matter, such as sticks, gravel and the like from entering the space between the sill and the gate and lodging against the sealing strip 26. Small particles of grit and other foreign matter passing the flange 27 will be carried by the sealing strip 26 downstream, during the movement of the gate 20 from open to closed position, to the rear portion of the sill 11 so that under normal conditions the depression 12 will be maintained relatively clean of foreign matter which might interfere with the functioning of the sealing strip 26.

The gate 20 may be operated by any suitable mechanism. In the present instance, the operating mechanism is shown as comprising an operating rod 31 pivotally connected at its lower end by means of a pin 32 carried by the end 19 and eccentrically disposed with respect to the axis of rotation of the gate.

The operating rod 31 extends upwardly in a notch 33 formed in the end wall or pier 14 and has its upper portion threaded, as at 34 (Fig. 6).

Mounted on the threaded portion 34 of the rod 31 is a nut 35 which is rotated by a worm gear 36 driven from a motor 37 or other source of power in the manner shown by Figs. 5 and 6.

The nut 35 and gear 36 are disposed within a housing 38 rotatably mounted on top of the pier 14, as shown in Figs. 3 and 6.

When the gate 20 is in a vertical or damming

position, as shown in Fig. 3, the pivotal connection of the rod 31 with the end 19 will be disposed at a point below the axis of rotation of the device, so that when it is desired to shift the position of 5 the gate 20 to lower the height of the water dammed up by said gate, the rod 31 can be pulled in an upward direction by its operating mechanism. In this way, the power required to operate the gate against the forces exerted there- 10 against by the dammed up water will not be excessive and the gate can be easily turned upon its journals 21.

On the other hand, due to the disposition of 15 the gate 20 within the depression 12, when said gate is in the horizontal position shown in Fig. 4, the force of the water flowing over the dam will be such that the gate can be readily elevated towards its vertical or damming position, by moving 20 the operating rod 31 downwardly through the action of its operating mechanism.

Having thus described my invention, what I claim is:

1. A dam comprising a sill, upstanding end walls at each end of the sill, a circular pocket 25 formed in each end wall, a movable gate, circular ends on the gate in the form of cylindrical drums rotatably mounted within the end pockets respectively of the dam, and mechanism eccentrically connected to a circular end of the gate 30 for operating said gate.

2. A dam comprising a sill, upstanding end walls at each end of the sill, a circular pocket formed in each end wall in a plane above the 35 sill, a movable gate having ends in the form of cylindrical drums adapted to rotate within said end pockets, a journal mounted concentrically in each end pocket and carried by the end wall of the dam, a bearing formed concentrically in each 40 cylindrical drum for receiving each journal, and

mechanism eccentrically connected to an end of the gate for operating said gate.

3. A drum comprising a sill, upstanding end walls at each end of the sill, a circular pocket formed in each end wall, a movable gate spanning the space between the end walls of the dam, said gate having a cylindrical drum at each end thereof disposed in said pocket, and supporting means for the gate concentrically disposed within said pockets and journalled to the end walls of 10 the gate for rotatably supporting the gate in the dam.

4. A dam comprising a sill formed on the bed of a stream, said sill having an arcuate depression formed longitudinally in its upper surface, 15 upstanding end walls at each end of the sill, a circular pocket formed in each end wall, a movable gate having a curved body portion adapted to conform to the arcuate depression in the sill when the gate is in lowered position, said gate 20 having ends in the form of cylindrical drums adapted to rotate within the end pockets respectively of the dam, supporting means for the gate comprising a journal mounted in each pocket and carried by each end wall of the dam, a bearing 25 formed concentrically in each cylindrical drum for each journal, means for sealing the joint between a longitudinal edge of the gate and the sill, operating mechanism for the gate comprising an operating rod pivotally connected at its 30 lower end to an end drum of the gate, said pivotal connection being eccentrically disposed with respect to the axis of rotation of the gate, and means for moving said rod upwardly and downwardly to impart rotary movements of the gate 35 from a substantially vertical position in which the gate is outside of the arcuate depression to a substantially horizontal position in which the gate is disposed within the depression.

HARRY E. SMYSER. 40
